Atty.

UNITED STATES PATENT OFFICE.

STEPHEN FAITH, OF CHICAGO, ILLINOIS.

RADIATOR-CAP-ORNAMENT HOLDER.

Application filed November 17, 1926. Serial No. 148,835.

This invention relates to an ornament and signal supporting means for the radiator cap of an automobile.

It is a very common practice at the present time to utilize the radiator cap of an automobile as a support for a signal or an ornament. These radiator caps are quite standard and usually comprise a cap having a hinged and centrally apertured cover. In 10 this aperture is fitted either the stem of a signal, such as a motormeter, or the stem of an ornamental figure. To meet the popular demand for such devices it is highly desirable that a support be provided which will 15 permit use of both a removable ornament and an indicator, for at present with known forms of caps, as above described, it is only possible to employ an indicator in the aperture of the cap, or an ornament, but never 20 both.

Accordingly, the main objects of this invention are to provide a novel support or holding means for a radiator cap, which will permit use of both an ornament and an indicator; to provide an improved cap including such novel holder; and, lastly to provide such a device which will be attractive in appearance to meet the popular demand at a reasonable cost.

These very desirable objects are achieved in a radiator cap having a hinged, apertured cover, said cap being provided with an integrally formed, forward extension provided with a socket adapted detachably to receive the stem of an ornament to support the same. An indicator is then placed in the aperture of the cap, and thus it is possible to employ both an indicator and an ornament in association with a radiator cap in 40 a most attractive manner, as will presently appear.

Referring now to the accompanying sheet of drawings, wherein has been shown an illustrative embodiment of this invention,—

Figure 1 is a top plan view of the improved radiator cap and support; and

Figure 2 is a side elevational view of the same, with an indicator and an ornament shown in combination therewith.

The radiator cap shown comprises a cast-

ing having a cap or body part 5, formed with a threaded nipple 6 for attachment in a complementarily threaded filler plug of a radiator, not shown. The cap includes an integrally cast, forwardly protruding support, or arm 7, at the free or forward end of which is a vertical socket 8, in an enlarged knob part 9. The top of the cap body 5 and arm 7 are flat and lie in the same horizontal plane in the embodiment illustrated. 55

The cap part 5 carries on a hinge 10, a cover 11, having a central aperture 12. The cover has a tongue 13, which extends forwardly into a socket 14, disposed in the arm 7 at its juncture with the body 5, as shown. 60 A spring catch 15 lies in this socket to catch the tongue 13 to lock the cover, as will be understood.

It can now be seen that the aperture 12 in the cover will receive the stem of an indicator, such as a motormeter 16, while the socket 14 will receive the stem of a figure or other ornament 17. These stems will be detachably secured in place in any suitable manner. In filling the radiator with water, 75 only the indicator need be lifted with the hinged cover, as the ornament is carried in a holder which is integral and remains stationary with the cap body. This is an advantage, as it is unnecessary to lift the additional weight of the holder and ornament when filling the radiator. 80

Obviously, the cap structure of this invention meets all of the desirable objects heretofore recited. The device is simple and, in 85 appearance, altogether attractive, it permitting utilization of the radiator cap for both practical and ornamental purposes.

It is the intention to cover all such changes and modifications as do not depart from the 90 spirit and scope of this invention, as is indicated in the following claims.

What I claim as new is:

1. In a radiator cap comprising a body, an extension connected to the body and formed 95 with a socket in its free end to support an ornament, a hinged cover for the body, a tongue on the cover, and a locking means for the tongue located in the extension.

2. In a radiator cap comprising a body, an 100

integrally formed, forwardly extending arm on the body having formed in its free end a knob provided with a vertical socket adapted to receive an ornament, a hinged cover in the body, and a locking means for the cover located in the arm.

3. In a radiator cap assembly, the combination of a cap having a hinged apertured

cover, an indicator supported therein, an arm extending from said cap and having a socketed knob at its free end, an ornament supported in the knob, and locking means for the cap located in said arm. 10

Chicago, Illinois, November 12th, 1926.

STEPHEN FAITH.
